UNITED STATES PATENT OFFICE

PAUL JUBIEN AND PAUL NAEHEE, OF CHICAGO, ILLINOIS; SAID JUBIEN ASSIGNOR
TO SAID NAEHEE

GYRATORY AGITATOR

Application filed October 3, 1924. Serial No. 741,389.

Our invention relates to the class of sifting and agitating machinery which is used with a gyratory or rotating movement. Where devices of this kind have heretofore usually been given a rotatory or swinging motion by means of weights carried on swinging arms or levers pivotally attached to the sieve box, but weighted arms in similar constructions create leverage and strain which tend to cause the mechanism to bind and to work with difficulty together with unnecessary loss of power. It is the object of our invention to provide a simple and effective device for operating sieves or riddles of the class described, to do away with rotating arms or weights which may have a binding action, and to provide a smooth and durable mechanism which may be operated with the highest degree of efficiency.

The principles of our invention are illustrated in the drawings in which Fig. 1 shows a vertical elevation of my improved sifting machine as supported by suspending rods; Fig. 2 is an enlarged sectional view of the same on line 2—2 of Fig. 1; Fig. 3 is a sectional view on the line 3—3 of Fig. 2; Fig. 4 shows an enlarged top view of a modified form of the apparatus; Fig. 5 is a section on the line 5—5 of Fig. 4.

Further describing our invention with reference to the drawings in which like characters of reference denote like parts throughout: Numeral 1 indicates a box or other support adapted to receive screens of desired mesh and arranged in any preferred relation to each other to receive any object which it is desired to submit to gyratory agitation. Said box or support is suspended from a ceiling or any other suitable object by slings or rods 2 which should be of some non-crystallizable material such as wood, and attached by means of brackets 3 to a stationary support 4. The lower ends of the rods may be received by washers 5 placed on the under side of the screen box 1. On the under side of the screen box by means of the ears 6 is attached a metallic casing 7 having vertical walls 8. On the lower side of said casing and centrally thereof is a depending member 10 having a centrally contained shaft 11

mounted in frictionless bearings 12. A pulley 13 is mounted on the lower end of said shaft for the purpose hereinafter described. On the upper end of shaft 11 is secured a radial arm or lever 15 and securely held thereon against rotation by the set screw 16 or other suitable means. The projecting portion of said arm has elevated flanges 17; the proximate facing portions of said flanges are trued to form a run-way between them within which is received an elongated block 18. A vertical pin or shaft 20 is rigidly attached to said block and a heavy roller 21 provided with frictionless bearings 22 and 23 is adapted to revolve thereon. A pulley 30 is mounted on a power shaft 31 and journaled in a hanger 32. A bracket 35 carries a plurality of flanged pulleys 36 and 37 around which a belt 38 is passed to connect pulley 30 with pulley 13 and transmit the power of shaft 31 to the shaft 11. When the power is so applied, the crank 15 will be caused to revolve taking with it the roller weight 21. As the power increases, the centrifugal force of revolution will cause the face of said roller to roll upon the inner face of the casing 8, thereby imparting a combined gyrating and shaking motion to the casing and also to the sifter box and sieves to which the device is attached. It will be seen that with only the power necessary to impel the roller or wheel in its circular path, a very powerful thrust is delivered at all points of the track corresponding to all portions of the circle through which the screen moves. It will further be seen that there is no strain on bearings and that the mechanism is fitted to withstand the strongest thrust of centrifugal force which may be exerted against the containing walls irrespective of the speed at which the weight wheel or wheels rotate. The apparatus shown in Figs. 4 and 5 is designed for larger and heavier machines than that described in the preceding paragraphs. Its operation is similar, being provided with a rotating arm 15' and a plurality of separate rollers 21' operating in a head 21'' which is attached to the arm 15'. The said rollers are mounted on shafts 40 which may move in radial slots 41 and which are slidably connected to the

arm 15' and whose peripheral faces bear upon the inner face or run-way of the casing 8'.

We claim:

1. In a gyratory agitator; a suspended support for an object to be agitated, a casing attached to the said support and having a circular track therewithin, a shaft journaled in said casing axially aligned with the central axis of said track, a lever extended radially from said shaft within said casing, and a multiplicity of wheels within the casing operatively connected with said lever and adapted to ride on the track by centrifugal force when impelled by said lever.
- 15 2. In a gyratory agitator; a suspended support for an object to be agitated, a casing attached to the said support and having a circular track therewithin, a shaft journaled in said casing axially aligned with the central axis of said track, a lever extended radially from said shaft within said casing, and a plurality of wheels extendably mounted on said lever and adapted to bear and rotate upon said track by centrifugal force when said lever 25 is rotated by said shaft.

In witness whereof, we have hereunto set our hands, at Chicago, Illinois, this 24th day of September, 1924.

PAUL JUBIEN.
PAUL NAEHER.
